UNITED STATES PATENT OFFICE.

CHARLES GEORGE JOHANNESMEYER, OF GLENDALE, OHIO.

PLANER FEED DEVICE.

1,303,675.

Specification of Letters Patent. Patented May 13, 1919.

Application filed July 29, 1918. Serial No. 247,121.

To all whom it may concern:

Be it known that I, CHARLES GEORGE JOHANNESMEYER, a citizen of the United States, residing in Glendale, Hamilton county, Ohio, have invented certain new and useful Improvements in Planer Feed Devices, of which the following is a specification.

This invention, while useful in other situations, has been devised primarily as a device for use in connection with the feed of metal planers, and the invention will be readily understood from the following description taken in connection with the accompanying drawing in which:

Figure 1 is an end view of a planer-rail provided with an embodiment of my improved feed-device, a removable portion of the casing-cover being omitted, and the main casing appearing in vertical section in the plane of line *c* of Figs. 2 and 3.

Fig. 2 a front elevation of a portion of the planer-rail and feed-device:

Fig. 3 a vertical section of a portion of the feed-device in the plane of line *a* of Figs. 1 and 4:

Fig. 4 a plan of a portion of the device: and

Fig. 5 a vertical section of the clutch-throwing lever in the plane of line *b* of Fig. 2.

A diversity of scales is employed in the drawing.

In the drawing:

35 1, indicates the end of the planer-rail: 2, one of the feed-screws of the rail: 3, the other feed-screw of the rail, present on the assumption that the rail carries two heads:

40 4, the feed-rod of the rail:

5, a casing secured to the end of the rail and serving to cover mechanism thereat:

6, the usual splined shaft for bringing the feed-motion from the lower works of the 45 planer up to the end of the rail:

7, a driving-gear oscillated by the oscillation of the splined shaft: and

8, pinions loose upon the outwardly projecting portions of the feed-screws and 50 feed-rod and gearing with each other, the intermediate one of them engaging the gear 7.

As thus far described the device may have the usual form and mode of operation. It 55 is the duty of the splined rod 6 to turn a measured degree in one direction and then

the same degree in the reverse direction, this motion of the splined rod giving to gear 7, to which the rod is bevel-gearred, a similar motion of oscillation, and the gear 7 giving 60 to the pinions 8 the same motion of oscillation. Usually the pinions are pawl and ratchet devices, or so-called click-boxes, which can be adjusted to cause the oscillation of the pinions to become effective upon 65 their feed-screws or feed-rod in selected direction, or to be neutral. The present device presents a construction for the pinions to endow them with pawl and ratchet quality, and as the three pinions are alike particular description need be given to but one of them, and it is to be taken as understood that the shaft to which the described pinion pertains is either the feed-rod or feed-screw, in other words, a shaft, threaded or otherwise, to be rotatively advanced intermittently.

Proceeding with the drawing:

9, indicates a counterbored collar capable of sliding on the shaft, the feed-screw 2 in 80 the selected instance:

10, facial ratchet-teeth formed on one end of this collar:

11, a pin through the shaft, its projecting ends being straddled by notches in the 85 counterbored end of the collar so that the collar may slide but not turn upon the shaft:

12, a spring disposed in the counterbore of the collar and acting compressively between the pin 11 and the bottom of the counterbore:

13, a second counterbored collar with its face spaced apart from that of the collar 9:

14, facial ratchet-teeth upon the second 95 collar, these teeth being arranged to ratchet in the direction opposite that of teeth 10:

15, a pin for the second collar:

16, a spring for the second collar:

17, an enlargement fast upon the shaft 100 between the two collars and limiting the approach of those collars toward each other under the influence of their springs, this enlargement being illustrated in the present instance as a thimble separably pinned upon 105 the shaft:

18, a hub of some length at one side of the pinion 8, this hub being bored to turn and slide upon the collar 9:

19, a circumferential groove in this hub: 110

20, a collar fast within this hub and adapted to slide on the enlargement 17, and

having each of its ends provided with facial ratchet-teeth to coöperate with the ratchet-teeth of the collars 9 and 13:

21, a counterbored hub removably secured 5 to the shaft and adapted to coöperate with the casing in protecting the collar 13, these hubs 21 being provided with a circumferential series of graduations to measure the angular rotation of the shaft, particularly 10 when the shaft is turned by hand:

22, a bearing secured removably to the wall of the casing in front of the shaft to which the pinion pertains:

23, a cylinder fitted to turn in this bearing; 15 24, a lever secured to the outer end of this cylinder:

25, a block adapted to fit sidewise in the groove 19:

26, a cylindrical shank of this block, fitting an eccentric bore in the cylinder 23: 20 and

27, a spring detent adapted to engage countersinks in the periphery of the cylinder and 25 yieldingly hold the lever 24 in either of its extreme positions or in its neutral position.

Enlargement 17, which is separably pinned to the shaft, is made in the manner indicated merely to facilitate the construction and assembling of the parts, the purpose 30 of this enlargement being simply to limit the inward movement of the ratchet collars 9 and 13.

As the parts appear in Fig. 3 the pinion together with its hub and its collar 20 are in 35 neutral endwise position and the pinion may make its oscillations without effect upon the shaft. But if the pinion be shifted to the left, and there held, then the teeth at the left end of collar 20 will engage the teeth 10 of collars 9, and thereupon the oscillating motion of the pinion in one direction will be transmitted to the shaft, while upon the occurrence of the oscillating movement of the pinion in the other direction the engaging 40 teeth will ratchet past each other, collar 9 moving to the left against the resistance of its spring, and no motion will be given to the shaft. The result is that the shaft will be advanced, clockwise, intermittently. If, 45 however, the pinion be shifted to the right, then the intermittent advance of the shaft will be effected through the medium of collar 13, and the shaft will be turned intermittently in non-clockwise direction. Analysis 50 of the toothed collars 9 and 20, considered as a couple, will show that the teeth constitute, in effect, a pawl and ratchet, and that the performance would be the same if all of the teeth, except one, were omitted from one 55 member of the couple. And, similarly, as regards the couple formed by collars 20 and 13.

The graduated collar 21 serves in protecting projecting parts and also serves in indicating the measure of rotative advance of 60

the shaft while it is being turned either by the oscillation of the pinion, or by hand.

Normally the handle 24 is vertical and held so by the spring detent, and in this position the ratchet collar 20 is neutral, and no 70 rotation is transmitted to the shaft. If the handle 24 be turned a quarterway to the right, where it will be again held by the spring detent, the block 25, fitting the groove 19 in the pinion, will cause the shifting and 75 holding of the pinion to the right so that the oscillations become effective upon ratchet-collar 13, and the shaft be turned intermittently in non-clockwise direction. If the handle be turned to the left, then the ratchet-collar 9 becomes the effective one and the shaft becomes turned intermittently in clockwise direction. Assuming the shaft to be a right-hand feed-screw then the direction of the handle 24 indicates the direction of feed of 80 the part moved by the feed-screw. The pinion can be thrown to the right or to the left or to the neutral while the parts are in operation, a result not conveniently attainable with the usual arrangement where the pinion 85 is a click-box carrying a pawl. The bearings 22, for the eccentric cylinders, are flanged and removably secured to the front wall of the casing.

It is to be understood that the construction 90 of the device particularly set forth constitutes but a single exemplification of my invention, my intention having been to set forth the principle of the invention and the best mode in which I at present contemplate 100 applying that principle.

I claim:

1. A feed device comprising, a shaft, a non-rotary spring-pressed sliding collar thereon, ratchet-teeth on the face of the collar, a pinion adapted for oscillation and fitted loosely with reference to the shaft and adapted for sliding adjustment, a collar carried by the pinion and having ratchet-teeth adapted for engagement with the teeth of the first-mentioned collar, a stop independent of the pinion to limit the movement of the collar under the influence of the spring, and means for adjusting the pinion endwise and for holding it against endwise displacement, combined substantially as set forth. 110

2. A feed-device comprising, a shaft, a pair of non-rotary spring-pressed sliding collars thereon, ratchet-teeth on the inner faces of the collars, a pinion adapted for oscillation and fitted loosely with reference to the shaft and adapted for sliding adjustment, a collar carried by the pinion and having ratchet-teeth adapted for engagement with the teeth of the other two collars, stops to limit the movement of the collars under the influence of their springs, and means for adjusting the pinion endwise and for holding it against endwise displacement, combined substantially at set forth. 120 125 130 135 140 145 150 155 160 165 170 175 180

3. A feed-device comprising, a shaft, a pair of pawl and ratchet members mounted on the shaft, means to prevent the turning of these members on the shaft, a third pawl and ratchet member loose on the shaft between the two other members thereon and normally free from them, means for adjusting the third member endwise on the shaft so as to form an engaged member of a pawl and ratchet couple with either selected one of the two first-mentioned members, means for holding the third member against endwise displacement after adjustment, and means for giving motion of oscillation to the third member, combined substantially as set forth. 5
- 10 4. A feed device comprising, a shaft, an enlargement fast thereon, a pair of counter-bored sliding collars on the shaft at each side of the enlargement, springs yieldingly pressing the collars against the enlargement, ratchet-teeth on the inner faces of the collars, an oscillating pinion normally loose with reference to the shaft and mounted to slide on one of said collars, a collar carried by the hub of the pinion and engaging said enlargement and provided with ratchet-teeth upon its opposite faces normally free from but adapted to engage the teeth of the first-mentioned collars, and means for adjusting the pinion endwise and for holding it against endwise displacement, combined substantially as set forth. 20
- 15 5. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 25
- 20 6. A feed-device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 30
- 25 7. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 35
- 30 8. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 35
- 35 9. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 40
- 40 10. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 45
- 45 11. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 50
- 50 12. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 55
- 55 13. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 60
- 60 14. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 65
- 65 15. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 70
- 70 16. A feed device comprising, a shaft, an oscillating sliding pinion normally loose with reference to the shaft and having a circumferentially grooved hub, pawl and ratchet mechanism connecting the pinion and shaft and adapted to be thrown into and out of action by the sliding of the pinion, a casing-wall in front of the pinion, a bearing disposed in said wall, a cylinder fitted to turn in said bearing, a block fitting sidewise in the circumferential groove of the hub of the pinion and having a shank journaled eccentrically in said cylinder, a hand-lever on the cylinder forward of the casing-wall, and a detent for holding the cylinder in angularly adjusted position, combined substantially as set forth. 75
